UNITED STATES PATENT OFFICE.

GEORGE ALBEN E. LUNDELL, OF CHICAGO, ILLINOIS, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,401,544.

Specification of Letters Patent. Patented Dec. 27, 1921.

Application filed November 1, 1919. Serial No. 335,131.

To all whom it may concern:

Be it known that I, GEORGE ALBEN E. LUNDELL, a citizen of the United States, residing at Chicago, in the county of Cook and State of Illinois, have invented certain new and useful Improvements in Telephone-Exchange Systems, of which the following is a specification.

This invention relates to manually operated telephone systems in which the system is divided into districts, that is to say in which the subscriber's telephone lines are divided into groups, and the lines of each group terminate at the central telephone offices of the system.

It is the object of the present invention to provide an order circuit for the use of two operators, one in the answering office and the other in the called office, without the necessity of providing a pair of wires extending between the two offices.

Heretofore it has been the practice to operate such multi-office telephone systems over a call circuit or order wire, described on page 487 of McMeen & Miller's "Telephony," edition of 1912. The call circuit, or order wire, according to the usual practice, is a separate pair of conductors extending from one telephone office to another telephone office, and is employed exclusively by operators. When a subscriber originates a call, for example, the operator, who answers him, commonly known as the subscriber's or A operator, having obtained from him verbally the designation of the wanted subscriber's line, depresses a call circuit or order wire key corresponding to the office designation of the office in which the called line terminates. This key places her telephone set in operative connection over the order circuit to the telephone set of the "trunk" or B operator, located at the trunk board in the wanted office.

Upon hearing the numerical designation of a wanted line spoken, the "trunk" or B operator responds by verbally giving the number of an idle trunk which she chooses to use for the connection. She also inserts its plug into the multiple jack of the wanted subscriber, assuming, of course, that the called line is idle. The subscriber's or A operator meanwhile connects, by means of a well known cord pair, to the trunk line jack

assigned by the trunk operator, and the two subscribers are thus telephonically connected.

In large telephone offices there are, of course, a number of the subscriber's, or A operators, having the same work to do as the subscriber's operator just described. In the busy hours of the day, therefore, it often happens that several A operators depress their order keys to the same trunk operator at the same time, thereby establishing a telephone connection from all of their head sets to the order circuit. The shunting effect of a plurality of such head sets on the order circuit seriously affects the transmission, and since there is no way of indicating to these A operators which of them should take preference they all may speak at the same time. It has been the practice in the larger telephone systems to instruct the trunk or B operator that when several A operators attempt to pass orders simultaneously she should disregard all of the orders, and wait for them to take turns.

This has lead to a great deal of confusion, the poor grade of transmission obtained under such circumstances being an additional source of confusion.

An object of the present invention is to provide an order circuit for the exclusive use of the operators connected thereto, so that orders may be transmitted without confusion or loss in transmission.

It is a further object of the present invention to provide an improved method of choosing an idle trunk, and to provide a circuit whereby the number of this trunk may be indicated to the operator.

It is a further object to provide a circuit for holding a telephone connection from the subscriber's operator's head set to the order circuit until she takes up the assigned trunk.

Another object is to connect the trunk operator's telephone set to a trunk circuit appearing at her position, when a call comes in on that trunk, so that she may receive orders over such a circuit in the same manner as she receives orders over the order system previously used.

It is understood that the disclosure herein set forth is only one of a variety of expressions which the invention is capable of receiving, and that the scope of the invention

is not to be determined by it, reference being had to the appended claims for that purpose.

The invention will be understood more in detail by reference to the accompanying drawings wherein is disclosed so much of a telephone exchange system as is necessary to a full explanation of the invention.

Figures 1, 2, and 3, taken collectively, represent a connection from a calling to a called subscriber. Fig. 1 represents a part of the connection in the calling office; Fig. 2, which is to be placed immediately to the right of Fig. 1, represents the part of the system located in each called office, and Fig. 3, which is to be placed immediately below Fig. 1, represents a portion of the apparatus located in the calling office, and includes the master switch bank, and in skeleton form the outgoing end of a second trunk line circuit. Fig. 4 shows in detail the construction of the master switch bank. Fig. 5 is a chart indicating the relation of the principal units of the system, and shows diagrammatically the calling and called subscribers, and various offices of a multi-office telephone system.

The secondary line switch 63 shown at the right of Fig. 1, represents a trunk finding apparatus, and for the purpose of setting forth the invention I show a well known line switch of the type described in the British Patent #26,301 of 1906. Said line switch comprises an electro-magnet 44 with its plunger 48 and a bank composed of a number of bank spring sets, only one set being illustrated. The plunger 48 is pivotally fixed on armature 64 in such a manner that it can be rotated by the movement of the plunger shaft 65. In Fig. 3 there is shown the master switch 306 which controls the movement of the ratchet wheel 314 the plunger shaft 65 and a plurality of plunger arms, such as 48. Bank spring set 305 is a part of another bank spring set whose plunger arm is operated by the same plunger shaft 65 as plunger arm 48. The master switch 306 is adapted to control the positioning of plunger shaft 65 to carry all idle line switch plungers opposite the next idle trunk line in readiness to be seized on the next call.

The plunger arm 30 operable on the energization of electro-magnet 31 of the primary line switch is controlled by means of an additional master switch not shown. It is to be understood that this master switch as well as line switches such as 31, controlled by it, are mechanically independent of the master switch 306 and the line switch banks 305 and 63. The master switch 306 comprises a motor magnet 313, an auxiliary relay 303 and a differential relay 304. The latter is adapted to control the energization circuit of the motor magnet

313 which in turn controls the ratchet wheel 314. Referring to Fig. 4, the master switch bank 318 comprises the individual contact points such as 308, 315, 316, 317, separated from conducting segment 310 by the insulating strip 402 and is so arranged that when the wiper 312 engages the last contact point 316, and then on its next step is carried to the contact point 317 on the right, the upper part of wiper 312 slides on the spring 401. This provision is made in order that the wiper 312 in passing from the extreme left contact point 316 to the extreme right contact point 317 may not place the contact points such as 308 and 315 in connection with the conducting segment 310 whereby some interference might be experienced by the master switch. The energization circuit for the differential relay 304 is controlled by the wiper 312 and whenever the said wiper 312 engages a bank contact having the guarding circuit closed the differential relay 304 is caused to operate and this in turn energizes the motor magnet 313 until the wiper 312 is stepped into engagement with a bank contact having no guarding circuit closed. Incidentally the plunger shaft 65 is also rotated to carry all idle line switch plungers opposite the trunk line corresponding to the bank contact on which the wiper 312 stopped.

The electro-magnet 31, the plunger arm 30, and the bank spring set operated by the insulated ball 32 form part of the primary line switch co-operating with the secondary line switch 63 to seize an idle trunk. Only so much of the primary switch is shown as is necessary to an understanding of the invention, it being understood that any suitable trunk finding device may be used, and that the one shown in the drawings is similar to the secondary line switch 63 described above.

The subscriber at station 1, of Fig. 1, desiring to originate a telephone call to subscriber 200, Fig. 2, removes his receiver and closes thereby a circuit extending from grounded battery 2, the winding of line relay 3, conductor 4, contact 5 of relay 6, conductor 7, substation 1, conductor 8, and contact 10 of relay 6, to ground, energizing thereby relay 3, and closing the circuit of line lamp 11 at the contact 12. Relay 13 is a pilot relay common to a plurality of line lamps 11 for closing the circuit of a pilot lamp (not shown) to indicate to the operator when any of the associated line lamps are burning. The subscriber's operator upon noticing that line lamp 11 is lighted chooses plug 14 of one of those in her position which are not at the moment engaged, and inserts it into jack 15, establishing thereby a circuit from the grounded battery 16 through supervisory signal 17, resistance 18, plug 14, jack 15, and cut off relay 6 to ground; operat-

ing the relay 6 and opening contacts 5 and 10. This causes line relay 3 to become released and the line lamp 11 is thereby extinguished. A circuit is also closed from 5 grounded battery 20, lower left winding of repeating coil 21, supervisory relay 22, plug 14, jack 15, conductor 7, substation 1, conductor 8, jack 15, plug 14, upper left hand winding of repeating coil 21, for supplying 10 battery for operating the substation transmitter, and for operating relay 22. The operation of relay 22 closes at its front contact a shunt circuit by way of conductor 23, and resistance 24 around supervisory lamp 17. 15 The resistance 24 is of such value as to reduce the current through supervisory lamp 17 sufficiently to dim it to the point where its illumination will not be noticeable to the operator. The operator now closes listening key 25 and establishes a telephonic connection from her telephone set 26 to the right hand windings of repeating coil 21, and thus inductively to the calling subscriber. She ascertains over this circuit verbally the 20 number of the subscriber wanted.

The subscriber's operator now depresses the plunger 27 and closes thereby contact 28 establishing a circuit for operating relay 66 and for starting a trunk finding operation 25 which will now be described in detail.

The plunger 30 of the primary switch, as described in the British Patent 26,301 of 1906, always stands before the set of springs associated with an idle connecting circuit, 30 and upon sufficient energization of the electro-magnet 31 this plunger will be drawn forward forcing the insulating ball 32 thereof between the innermost springs of the set whereby each of the four springs of the set 35 is forced outwardly into engagement with its co-operating contact. The lead 33 associated through contact 34 with primary switch contact 35, leads to the master switch as shown in the above mentioned British 40 patent, whereby through action of well known means all of the remaining idle plungers of the group are moved to a position before the springs associated with the next idle trunk. Current is supplied through 45 lead 36 through the normally closed contact 37, but during the interval when the switch plungers are in transit from one position of rest to the next, the circuit is opened at contact 37 so that no finder mechanism can be 50 actuated during this interval.

Upon the closure of contact 28, as hereinabove described, current flows over the following circuit: battery 38, contact 37, conductor 36, left hand winding of electro- 55 magnet 31, contact springs 40 and 41, conductor 42, contact 28, to ground, causing the armature of electro-magnet 31 to be attracted, and the plunger 30 to force the insulating ball 32 between the springs of the 60 set before which the plunger is resting. 65

Contact 40 is disengaged from contact 41 and a circuit is established through the right hand winding of magnet 31, whereby the plunger arm 30 is held in its operated position independent of contact 37. This circuit is as follows: Battery 67, right hand winding of magnet 31, contact 68, conductor 42, contact 28 to ground. Contact 43 now closes a circuit originating at battery 301 of Fig. 3, and including contact 302 of 70 relay 303, conductor 320, left hand winding of electro-magnet 44 of the secondary line switch, contact 45 of this switch, conductors 46 and 47, contact 43 and the contact 28 of the key 27. This energizes the electro-magnet 44, and by attracting its armature 64, forces the plunger 48 between the innermost springs of the set before which this plunger stands. As has been pointed out, the electro-magnet 44 and the set of springs associated with plunger 48, as well as the spring set 305 and the master switch 306, 75 form part of a secondary trunk finder mechanism similar to the primary line switch and to that shown in British Patent 26,301 of 80 1906.

The insulating ball 50 having been forced in between the associated set of springs, contact 51 closes a circuit ground to conductor 307, contact 308, wiper 312, conducting plate 310, winding of relay 303, left hand winding of differential relay 304, to battery 311, and relay 303 is thus operated and holds contact 302 opened so long as the master switch arm 312 is contacting with 85 such terminals as 308 of busy trunks. The magnet 44 remains energized, and the plunger arm 48 remains in the operated position, by virtue of a circuit through the right hand winding of the magnet 44, contact 70, conductors 46 and 47, contact 43 of the primary line switch, contact 28 to ground, independent of the contact 302. The operation of relay 303 opens its contact 90 95 100 105 110 115 120 125 130 302 and disconnects the battery 301 from the conductor 320 and from the left hand windings of all line switch magnets whose plunger arms are associated with the plunger shaft 65. The operation of the differential relay 304 closes the circuit of the motor magnet 313 and the master switch 306 together with the plunger shaft 65 is rotated until the wiper 312 contacts with a nongrounded contact, that is, with the contact of an idle trunk, such as 321.

The operation of magnet 44, also closes the contact 104, for operating relay 85, which thereupon operates and locks itself through its own left hand front contact and resistance 105 to ground at the left hand back contact of relay 87. Relay 66, and magnets 31 and 44 are now grounded, by way of the left hand front contact of relay 85, independently of the contact 28 of the key and the operator now removes 130.

her finger from the plunger 27. Her head set nevertheless remains connected to the order circuit as before.

The operation of electromagnet 44 causes the closure of contacts 52 and 53. The operation of electromagnet 31 causes the closure of contacts 54 and 55. A circuit is now established from battery 56 through right hand winding of retardation coil 57, conductor 58, contact 55, conductor 60, contact 53, conductor 180, lower left hand winding of repeating coil 201, of Fig. 2, conductor 202, left hand winding of relay 203, conductor 204, upper left hand winding of repeating coil 201, conductor 178, contact 52, conductor 61, contact 54, left hand winding of retardation coil 57 to ground, energizing the relay 203 of Fig. 2.

A circuit is now closed from battery 205, 20 lamp 237, conductor 206, contact 207 of relay 203, conductor 208, back contact 210 of relay 243, conductor 211, back contact of relay 212, conductor 213, winding of relay 214, contact 215 of this relay, conductor 216, resistances 217, back contact 218 of relay 221 to ground. The consequent operation of relay 214 connects the operator's telephone set 223 into conversational relation with trunk line 178 and 180, over a circuit including the battery 238, the lower right hand winding of repeating coil 201, winding of supervisory relay 236, conductors 225, 235, contact 227 of relay 214, condenser 228, winding 230 of an induction coil, operator's receiver 234, conductor 233, contact 226 of relay 214, conductors 231 and 224, upper right hand winding of repeating coil 201 to ground 230.

Relay 214 remains in its operated position independent of contact 218 by virtue of a circuit from battery 205, lamp 237, conductor 206, contact 207, of relay 203, conductor 208, contact 210 of relay 243, conductor 211, back contact of relay 212, conductor 213, winding of relay 214, left hand front contact of this relay, conductor 220, winding of relay 221, contact of key 267 to ground. Accordingly relay 221 operates and opens at its back contact 218 the energizing circuit of all relays corresponding to relay 214 associated with the same operator's head set 223, one of these other relays being shown as 614; no such other relay can therefore be energized since no current can flow through the contact 615 and conductor 616, resistance 217, because the contact 218 is opened. It will be seen, therefore, that the B operator's head set 223 is connected to only one trunk of the group with which it is associated, and that the B operator is therefore provided with an exclusive conversational circuit over that trunk without being interfered with by any other operator. It is also apparent 65 from the operation of the system so far de-

scribed, that trunk conductors 178 and 180 cannot become connected to any A operator other than the one described, since a guarding ground has been placed upon the master switch bank contact 308 as soon as these 70 conductors were seized. The talking circuit from the A operator to the B operator is therefore now available for their individual and exclusive use while passing the order for the connection. 75

The complete order circuit may be traced as follows: The operator's induction coil 26, conductor 72, contact 73, of the relay 66, which as described above is in its operated position, contact 54 of the primary line switch, conductor 61, contact 52 of the secondary line switch, trunk conductor 178, upper left winding of the repeating coil 201, condenser 253, lower left winding of the repeating coil 201, trunk conductor 180, contact 53 of the secondary line switch 63, conductor 60, contact 55 of the primary line switch, contact 74 of the relay 66, condenser 75, the operator's head receiver 76 to the induction coil 26, the primary circuit of which is closed through the operator's transmitter 77 in a well known manner. In inductive relation with left hand windings of repeating coil 201 in the circuit described, are the right hand windings of 95 the same repeating coil and a circuit extends through them as follows: Grounded battery 238, lower right hand winding of repeating coil 201, relay 236, conductors 225, 235, contact 227 of relay 214, which it will be re- 100 called is now in its operated position, conductor 234, condenser 228, secondary winding 230 of the operator's induction coil, operator's receiver 234, conductor 233, contact 226 of relay 214, conductors 231, 224, upper right 105 hand winding of repeating coil 201 to ground 230. The primary winding associated inductively with the secondary winding 230 is in circuit with the B operator's transmitter in a well known manner. The telephone set 110 of the A operator is thus operatively connected with the telephone set of the B operator. The A operator gives verbally over this conversational circuit the numerical designation of the wanted line. It is, of course, 115 unnecessary for her to give the office designation since her selection of the key 27 caused a trunk to the selected office to become connected with her telephone set. The B operator makes acknowledgement by giving the trunk number of the circuit over which she is speaking, the illumination of the lamp 237 in the circuit previously described indicating to the B operator this trunk number, and its being necessary for 120 her only to glance at the number plate associated with the lighted lamp to determine the proper number to give.

Thus the A operator has been apprised of the trunk number and she inserts the plug 125 130

78 into the jack 80 of the designated trunk. A circuit is now established from battery 81, through supervisory lamp 82, resistance 83, plug 78, jack 80, winding of relay 84 to ground, lighting lamp 82 and operating relay 84. The latter in turn causes the operation of relay 87 over the circuit: battery 88, winding of relay 87, conductor 90, contact 86 of relay 85, conductor 91, front contact of relay 84 to ground. Relay 87 locks itself through its own front contact independent of the circuit through contact 86, and it also applies a ground connection, through its left hand front contact and conductor 104 to the master switch bank contact independent of the ground connection by way of contact 51 of secondary line switch 63.

Relay 87 also closes, at its contacts 92 and 93, the following circuit: Grounded battery 20, lower right hand winding of repeating coil 21, the marginal supervisory relay 94, conductor 95, plug 78, jack 80, contact 92, trunk line conductor 180, lower left winding of repeating coil 201, conductor 202, left hand winding of relay 203, conductor 204, upper left hand winding of repeating coil 201, trunk line conductor 170, contact 93, jack 80, plug 78, conductor 96, upper right hand winding of repeating coil 21 to ground, thereby providing a circuit for holding the relay 203 energized independent of the battery supply hitherto received through the retardation coil 57.

It will be seen that the A operator can insert the plug 78 into the jack 80 as soon as she has received the number of the trunk from the B operator, and that the relay 203 is held energized equally well from the battery 56, or from the battery 20.

40 The B operator picks up the plug 240 associated with the lighted supervisory lamp and tests the called subscriber's line in the usual manner. A busy line will have a potential on the sleeve of the jack 247, and this 45 potential will cause current to flow through the following circuit when the tip of the plug is touched to the jack: Conductor 241, contact 242 of the relay 243, conductor 244, winding 246 to ground. Winding 246 is 50 inductively related to the winding 230, and the flow of current through it induces a current through the latter, and also through the operator's receiver 234, indicating to the operator that the called line is busy.

55 Assuming that the called line is idle and that no current flows in this circuit, and that consequently no click is received by the operator when she tests the jack, she inserts the plug 240 into the jack 247. Current now 60 flows from grounded battery 205 through the lamp 237, conductor 248, winding of relay 243, conductor 250, plug 240, jack 247, conductor 251, winding of cut off relay 252, operating relay 243, and disconnecting the 65 busy test winding 246 from this circuit. The

circuits of relays 214 and 221 are broken at the contact 210 of relay 243, and the release of relay 214 disconnects the operator's telephone head set 223 from conductors 231 and 235. The release of relay 221 makes the set 70 available for use in connection with other relays corresponding to 214 of the other trunks of her position, one of which is shown at 614.

A shunt circuit is established around the 75 lamp 237 by way of conductor 206, contact 207 of relay 203, which is in its operated position, conductor 208, left hand front contact of relay 243, back contact of relays 254 and 255, through the winding of relay 80 256, to grounded battery operating relay 256, and also through the winding of relay 212 to grounded battery. The resistance of the winding of relay 256 is of such value as to cause the extinguishing of the lamp 237, 85 the battery at 205 being the same as that shown at 266.

The operation of relay 212 opens at its back contact the circuit by way of conductor 213 for a purpose which will hereafter be fully set forth.

The operation of relay 256 closes a circuit from a source of ringing current 257 through the winding of relay 254, contact 258 of relay 256, conductor 260, plug 240, 95 jack 247, conductor 261, the sub-station 200, conductor 262, the jack 247, the plug 240, the conductor 241, right hand front contact of the relay 243, conductor 263, front contact 264, to ground. The bell at the sub-station 200 is operated and when the called subscriber responds he introduces into the sub-station circuit the low resistance path through his transmitter. This causes an increase of current in the circuit of relay 100 105 254, just described, sufficient to operate said relay, and the opening of the contact of this relay removes a short circuit from around the winding of relay 255, and causes current to flow therein. The consequent operation 110 of relay 255 causes its front contact to be closed, and a short circuit then is placed around the winding of relay 256 through the battery 265, it being understood that the battery 265 is the same as that shown at 266. The release of relay 256, as the result of 115 the short circuit of its winding, causes contacts 264 and 258 to open disconnecting thereby the source of ringing circuit from the subscriber's line and restoring relay 254 120 to normal. A conversational circuit is now closed for operating the subscriber's transmitter at the sub-station 200, and for operating relay 236, as follows: Grounded battery 238, lower right hand winding of repeating coil 201, supervisory relay 236, the conductor 225, back contact of relay 256, conductor 260, plug 240, jack 247, conductor 261, sub-station 200, including the transmitter therein, conductor 262, jack 247, plug 125 130

65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

240, conductor 241, right hand front contact of relay 243, conductor 263, back contact of relay 256, conductor 224, upper right hand winding of repeating coil 201 to ground 230.

The operation of relay 236 closes the circuit of the low resistance right hand winding of relay 203, and thus increases the flow of current over trunk line conductors 178 and 180 sufficiently to operate the marginal relay 94. The operation of relay 94 closes a shunt circuit around lamp 82 through the resistance coil 103, whereby the lamp 82 is extinguished. Subscribers 1 and 15 200 carry on their conversation and upon restoring their receivers to the switchhooks at its termination, cause the release of relays 22 and 236, the latter in turn by opening the low resistance circuit of the right 20 hand winding of relay 203 causing relay 94 to retract its armature. The shunts 24 and 103, are therefore removed from the supervisory lamps 18 and 82, causing them to burn brightly and thus to indicate to the 25 operator that the conversation is finished.

The operator pulls out plugs 14 and 78, restoring relays 6 and 84 to normal. The release of relay 84 causes in turn the release of relay 87, and this opens the circuit by way of conductor 104 to the master switch bank 318, and frees the contact point 308 from ground, so that trunk conductors 178 and 180 become available for use on a subsequent call. The removal of plug 78 35 also causes the release of relay 203, and this in turn removes the shunt around lamp 237. The increase in current in the lamp 237 causes it to light, indicating thereby to the B operator that the plug 240 should be disconnected. Relay 255 is released upon the release of relay 203. The operator accordingly removes the plug and relay 243 retracts its armature. In case the A operator does not understand or remember the number of the trunk, and therefore refrains from plugging into the designated trunk, the response of the called subscriber 200 will be heard in her head set since electro-magnets 31 and 44 and relay 66 will not then have 45 been released and the conversational circuit will thus connect the called subscriber with the A operator instead of with the calling subscriber. She may then advise the called subscriber that an error occurred and request him to restore his receiver to the hook and she may disconnect the connection by operating the disconnect key 97. This connects the battery 98 through the resistance coil 101 in shunt with the winding of relay 55 85, it being understood that the battery 98 is the same battery as that shown at 102. The resistance 101 is of such value as to reduce the current flow through the winding of the relay 85 sufficiently to cause it to release. The restoration of the relay 85 to

normal, under such conditions, removes the ground supply to electro-magnets 44 and 31, causing them to restore their plungers 48 and 30, respectively, to normal, in readiness for a new call. Relay 203 is also released at this time, and causes the disconnect signal in front of the B operator to be lighted, whereupon the B operator pulls down the plug 240. The A operator can now set up a new connection in the same manner as 75 before.

Should the B operator inadvertently pull down the plug 240 while conversation is being carried on over it her telephone set will not become connected with the corresponding trunk circuit, the circuit of relay 214 being held open at the back contact of slow release relay 212. Relay 243 releases when the plug is removed under these conditions, and a circuit is closed from battery 205, lamp 237, conductor 206, contact 207 of relay 203, conductor 208, the contact 210 of relay 243, conductor 211, right hand armature front contact and winding of relay 212 to ground. Lamp 237 is caused to burn brightly by the current 90 in this circuit, indicating to the operator that there is a connection on the trunk associated with this lamp, and since her telephone set remains unconnected she will connect this trunk with the chief operator or supervisor. 95

Fig. 5 shows the arrangement of the various circuits and apparatus of a telephone exchange system, and shows at 1 the subscriber's station 1 of Fig. 1. 502 is a diagrammatic representation of the connecting apparatuses of the A operator's position, one of which is also shown in Fig. 1. 200, 506, 507, 508, 510, 511, 512, and 513, represent called subscriber's stations arranged in two groups, the group comprising stations 200, 511, 512, and 513 being provided with a trunk board 504 which comprises the apparatus shown at the left hand side of Fig. 2; subscribers' stations 506, 507, 508, and 510 are provided with a trunk board such as 505, and it is understood that this board may be wired the same as 504. At the trunk board 504 there is provided the trunk operator's set 234, and at the trunk board 505 there is wired the trunk operator's telephone set 534, the details of the connection of these telephone sets being shown in Fig. 2, and the operation thereof having been described above. Connecting the A operator's board 502 with the B operator's board 504 are several pairs of trunk conductors—178 and 180, being one pair, and 678 680 being another pair. Connecting the A operator's board 502 with the trunk operator's board 505 is a plurality of trunk conductors, one pair of which is designated 578, 580. The pair 678, 680, and the pair 578, 580 correspond in functions to the pair 178, 180, and the details of wiring are similar to those for 178, 180. The A operator's board 502 is provided with the key 27, and this key 130

27 causes the operation of trunk finder 63 for selecting an idle trunk line extending to the trunk board 504. Another key 527 is provided for causing the actuation of trunk 5 finder switch 563 which automatically selects an idle pair of trunk connections extending to trunk board 505. The wiring of the key 527 and the trunk finder 563 corresponds to that of key 27 and trunk finder 63, and it 10 will be readily understood that by manipulation of the key 27 the operator can cause the seizure of an idle trunk to office 504, and that by manipulation of key 527 she may initiate the operation of trunk finder 563 for selecting an idle trunk extending to trunk board 505.

In Fig. 5 there is indicated the connection from the trunk operator's telephone set 234 through contact of relay 214 to the pair of 20 trunk conductors 178 and 180 and the corresponding relay 614 associated with the pair of trunk line conductors 678 and 680. By means of these relays 214 and 614 the trunk operator's head set becomes connected with 25 their associated trunk line conductors. The operator's head set 534 at trunk board 505 is wired in a similar manner through the contacts of relays, one of which is shown at 514 for connecting this head set to a trunk extending to trunk board 505.

I claim as my invention:

1. In a telephone exchange system an answering operator's board, called subscribers' lines arranged in groups, a trunk board for 35 each group, a plurality of trunk lines extending from the answering board to each trunk board, an operator's telephone set at each of said boards, a key at the answering board for each group of trunk lines, automatic 40 selecting means actuated by the operation of the key for seizing an idle trunk line of the group, an order circuit for operatively connecting the answering telephone set and a trunk telephone set over the selected trunk line, and a relay for maintaining said automatic selecting means in its actuated position, whereby said order circuit is maintained independently of the key.

2. In a telephone exchange system an answering operator's board, called subscribers' lines arranged in groups, a trunk board for 50 each group, a plurality of trunk lines extending from the answering board to each trunk board, a key at the answering board for each group of trunk lines, automatic selecting mechanism actuated upon the operation of a key for seizing an idle trunk line of the group, and a locking relay for maintaining said automatic selecting mechanism in 55 its actuated position independent of the key.

3. In a telephone exchange system an answering operator's board, a trunk operator's board, trunk lines extending from one board

to the other, automatic selecting means for 65 seizing an idle trunk, a telephone set for each group of trunks, means individual to each trunk for operatively connecting a trunk to a telephone set, and means responsive to the initiation of a call on one trunk 70 for rendering inoperative the connecting means of the group.

4. In a telephone exchange system a calling subscriber's line, an answering operator's board, an operator's telephone set 75 thereat, called subscribers' lines arranged in groups, a trunk board for each group, a plurality of trunk lines extending from the answering board to each trunk board, manual connecting means for connecting the calling 80 subscribers' lines with a trunk line, automatic selecting means for operatively connecting the A operator's board to an idle trunk independent of said manual connecting means, and a relay for maintaining said 85 automatic selecting means in its operative position, and means for releasing said relay upon the employment of said manual connecting means.

5. In a telephone exchange system a calling subscriber's line, an answering operator's board, an operator's telephone set 90 thereat, called subscribers' lines arranged in groups, and a trunk board for each group, a plurality of trunk lines extending from the 95 answering board to each trunk board, manual connecting means for connecting the calling subscribers' lines with a trunk line, automatic selecting means for operatively connecting the answering operator's board to an 100 idle trunk independent of said manual connecting means, a relay for maintaining said automatic selecting means in its operative position, means operated by the employment of said manual connecting means for releasing 105 said relay, and a conversational circuit for operatively connecting the answering operator's telephone set with a called subscriber's line.

6. In a telephone exchange system an operator's board, an operator's telephone set thereat, a B operator's board, trunk lines extending from one board to the other, automatic selecting mechanism for operatively connecting to an idle trunk the A operator's 115 telephone set, a B operator's telephone set, means individual to each trunk line operative upon seizure of said trunk line for connecting the B telephone set to the trunk, and a locking relay for each trunk adapted to 120 disable the last mentioned means.

7. In a telephone exchange system an answering operator's board, a trunk operator's board, trunk lines extending from one board to the other, automatic selecting means for 125 seizing an idle trunk, a telephone set for each group of trunks, a relay individual to each trunk for operatively connecting a

trunk to a telephone set, and a locking relay adapted to open the circuit of said connecting relay.

8. In a telephone exchange system, an answering operator's board, called subscribers' lines arranged in groups, a trunk board for each group, a plurality of trunk lines extending from the answering board to each trunk board, a key at the answering board for each group of trunk lines, automatic selecting means actuated upon the operation of said key for seizing an idle trunk line of the group, an order circuit including the conductors of the selected 15 trunk and means for maintaining said selecting means operated independently of said key.

9. In a telephone exchange system, an A operator's board, an operator's telephone set 20 thereat, a B operator's board, trunk lines extending from one board to the other, automatic selecting mechanism for operatively connecting said telephone set to an idle trunk, means for initiating the operation of 25 said automatic mechanism and means for maintaining said mechanism in its actuated

position independent of said initiating means.

10. In a telephone exchange system, a calling line, an A operator's board, a telephone set thereat, trunk lines extending from said board, means for selecting an idle trunk line, means for connecting said calling line to said idle trunk line, a start circuit for said selecting means operated independent 35 of said connecting means and means for maintaining the selecting means in its operated position.

11. In a telephone exchange system, a calling line, an A operator's board, a telephone 40 set thereat, trunk lines extending from said board, means for selecting an idle trunk line, means for connecting said calling line to said idle trunk line, a start circuit for said selecting means operated independent 45 of said connecting means and means independent of said start circuit for maintaining the selecting means in its operated position.

In testimony whereof, I hereunto set my hand.

GEORGE ALBEN E. LUNDELL.
